UNITED STATES PATENT OFFICE

2,263,163

SLOPE INDICATOR

James O. Cornell, Falmouth, Ky.

Application October 2, 1940, Serial No. 359,422

1 Claim. (Cl. 33—207)

The present invention relates to new and useful improvements in indicators designed for use by grading contractors and others in building uniform slopes on embankments, excavations and the like and has for its primary object to provide a spirit level attachable to a string that may be extended along the slope line during construction, at intervals, to keep the line of slope within the desired predetermined slope limit. The spirit level has an elongated arm at one end with notches at intervals for the purpose of finding the predetermined slope or grade.

A further object is to provide a device of this character which may be easily and quickly set up in the desired position with respect to the slope and which at the same time is simple and practical in construction, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof wherein like numerals refer to like parts throughout, and in which—

Figure 1 is a sectional view through a bank showing the indicator mounted in position relative thereto,

Figure 2 is a side elevational view of the indicator,

Figure 3 is an end elevational view thereof, and

Figure 4 is a sectional view taken substantially on a line 4—4 of Figure 2.

Referring now to the drawing in detail, wherein for the purpose of illustration I have disclosed a preferred embodiment of the invention, the numeral 5 designates a bank which it is desired to grade and the numeral 6 designates the grade or slope indicator generally which is supported on a string 7 extending from a lower post 8 and upper post 9.

The indicator comprises a spirit level 10 mounted in an elongated base 11 and at one end of which rises a short hanger member 12 having an upwardly inclined slotted opening 13 formed in one edge thereof for hanging on the string 7 and at the opposite end of which is a similar hanger designated at 14. At the bottom end of

the hanger 14 is a hinge member 15 to which is hingedly attached a relatively long upstanding hanger member 16. One edge of the hanger member 16 is provided with vertically spaced upwardly inclined slotted openings 17 adjacent to each of which the slope scale designated at 18 is displayed.

The slotted openings 17 are likewise adapted to receive the string 7 at a point above the lower hanger, 12, as illustrated in Figure 1 of the drawing. In the operation of the device, presuming there is a fill to be made adjacent the bank to level the same to a predetermined slope from the shoulder to the original ground at a ratio of 2 to 1, the string is inserted in the proper slotted openings indicated on the hanger 16 and the stake 8 set in the proper position so that the spirit level will be supported in a true horizontal plane. The position of the string will then indicate the extent of fill to be made.

A spring clip 19 secured to the fixed member 14 engages one edge of the pivoted hanger 16 to secure the latter in an upright position.

When the indicator is not in use the hanger member 16 may be swung under the base 11 of the spirit level into the dotted line position as shown in Figure 2 of the drawing, and secured by a second spring clip 20 attached to the base 11, whereby the same may be conveniently carried in the pocket of a person.

It is believed the details of construction, manner of use and advantages of the device will be readily understood from the foregoing without further detailed explanation.

Having thus described the invention, what I claim is—

A slope indicator comprising a spirit level, an elongated base for the level, a pair of substantially fixed hangers secured to the ends of the base in upstanding parallel relation, a pivoted hanger attached to one of said fixed hangers and rising above the latter, and adapted for swinging into a position flatwise against the base, each of said hangers having upwardly inclined notches in an edge thereof adapted to receive a supporting rope, and said notches of the pivoted hanger having indicating indicia adjacent thereto.

JAMES O. CORNELL,
